UNITED STATES PATENT OFFICE.

JOHN PETERSON, OF MAYWOOD, ILLINOIS, ASSIGNOR TO COMBINATION BLOW TORCH MANUFACTURING COMPANY, OF MELROSE PARK, ILLINOIS, A CORPORATION OF ILLINOIS.

BRANDING IRON.

Application filed February 8, 1924. Serial No. 691,371.

To all whom it may concern:

Be it known that I, JOHN PETERSON, a citizen of the United States, residing at Maywood, in the county of Cook and State 5 of Illinois, have invented certain new and useful Improvements in Branding Irons, of which the following is a specification.

The present invention relates to branding irons particularly intended for use upon 10 torches which emit a heating flame against the rear of the iron. The principal object of the invention is to provide a novel branding iron in which all the characters employed in making the brand will be equally 15 heated and well heated, and in which the heat will be held a sufficient time to permit each branding operation to be completed and well performed, while allowing such operations to take place with that frequency 20 found desirable in practice.

The invention will be best understood in respect to its several features and advantages upon reference to the following detailed description taken in connection with 25 the accompanying drawing and the scope of the invention will be particularly pointed out in the appended claims.

In said drawing, Fig. 1 is a side elevation of a torch upon which is located a branding 30 iron constructed in accordance with the present invention, the torch being shown in elevation and the branding iron and its attaching means in vertical section; Fig. 2 is a face view of a modified branding iron arranged for the attachment of removable 35 branding elements; Fig. 3 is a transverse section of said modified branding iron with one of the elements in position, the section being taken on a plane indicated by the line 3—3 of Fig. 2; Fig. 4 is a vertical section of a still further modification in which the branding elements are also removably associated, the plane of section being indicated by the line 4—4 of Fig. 5; Fig. 5 is a perspective view of the latter modification; 40 and Fig. 6 is a longitudinal section through a portion of the same illustrating particularly the way in which the branding elements are held in the body of the iron. Throughout these views like characters refer to like parts.

Referring to the drawing in detail, 10 designates the body of the torch which is bored out so as to provide a central mixing and combustion chamber 11. A downwardly ex-

tending tubular shank 13 and an associated tube 14 connect the torch with its fuel supply tank 15. A pump is employed to pump air into the tank 15 and thereby place the fuel, which is in liquid form, under pressure. Ordinarily the fuel employed is gasoline. A suitable passage from the opening in shank 13 leads to the combustion chamber by way of the needle valve 19 located at the forward end of the valve rod 20 which, in turn, is provided with an angularly disposed handle 21 by which the valve 19 may be adjusted. A fuel pan 30 serves to heat the torch at starting. Air is supplied to the combustion chamber 11 through the openings 31. The finger piece 33 enables the torch to be readily handled.

The torch construction need not be described with great particularity because the same constitutes in itself no part of the present invention, and is fully illustrated and explained in my prior application Serial No. 480,017, filed June 24, 1921, issued as Patent No. 1,487,359, dated March 18, 1924, and reference may be had to that case 75 for a fuller understanding of the torch structure.

The present application is in part a continuation of said prior case, the specific disclosure of Figs. 4, 5 and 6 being added to 80 the portion divided out of the parent case.

As clearly shown, the branding irons herein disclosed are attachments to be used upon the torch disclosed, or upon like torches or their equivalents.

The first to be described is branding iron 45 shown more particularly in Fig. 1. This branding iron comprises a relatively flat body 46 having branding element 47 on the one side and a flame impinging surface on 95 the other. The latter surface has its superficial area increased by reason of the projections or points 49 which extend outwardly from the body 46 and are integral with it. Since all are of metal, the flame which impinges against these points has its heat more readily conducted to the branding element 47. The latter may be of any preferred shape. In some instances it will consist of a letter, in others a mark or some distinguishing character, and in still others perhaps a word. The body 46 is provided on its rear face with a boss 50 which is drilled out for the purpose of receiving the forward end of a pin 41 associated with the discharge 100 105 110

end of the torch 10. A set screw 51 firmly secures the branding iron to the pin. The latter extends at its rear end into a similar opening in a boss 43 formed upon the body 5 of the torch 10, and a similar set screw 44 serves to hold the pin 41 in place. By the use of these parts the branding iron 45 is firmly secured in place upon the outer end of the body of the torch in line to receive the 10 flame emitted from its adjacent discharge end, and at the same time the arm may be readily removed for the replacement of another iron or other attachments when desired.

15 As just pointed out, when the parts are properly assembled the branding iron lies directly in front of the discharge opening 32 of the torch combustion chamber 11. Consequently the flame coming from that 20 chamber will impinge upon the surface 48 and projections 49. In order to prevent the flame from flaring in such a way as to burn or otherwise disfigure the object being branded, whether animate or inanimate, I 25 provide means for deflecting the flame backward away from the plane of the body 46, and consequently away from the object. In the present instance I employ a peripheral flange 52 which extends rearwardly 30 from the body 46, and by reason of its inclined wall 53 reverts the flame. Obviously, other arrangements may be employed for bringing about this same advantage. It is 35 also apparent that the flange 52 need not have the inclined wall 53 such as I have illustrated.

Instead of having the branding element 40 fixed to and forming a part of the branding iron, I am employing a branding iron of the form shown in Figs. 2 and 3 wherein the body 54 is similar to the body 46 but has on its front face merely two ribs 55 between which a removable branding element 56 may be secured by means of one or more 45 bolts 57 and nuts 58. The forward end of the iron 56 contains the marking elements 59 as will be apparent. In this instance the inner faces of the ribs 55 diverge outwardly and the portion of the branding element 56 which engages them is wedge-shaped so as to closely fit against these 50 faces. With this construction a space at the lower end of the branding element would still allow for a wedging fit between 55 the faces of the element and the engaged faces of the ribs. In this instance the body 54 is provided with a projection 60 which takes the place of the projections 49 of the earlier form. It is also provided with a 60 flange 61 which corresponds to the flange 52 on the first form. A similar boss 62 and a set screw 63 co-operate with the pin 41 to hold the iron in position upon the end 65 of the torch.

Again, the body of the branding iron may

take the form of the body 70 in the form of invention shown in Figs. 4, 5 and 6. In this instance the flange impinging surface is characteristically the same as illustrated in Fig. 1 and comprises the flat surface 48 70 from which projecting points 49 arise, and the outer edge is provided with the reverting flange 52. A boss 50 is apertured in like manner for the reception of the forward end of the pin 41. The set screw 51 75 performs the same function as before.

The opposite side of the body 70 in this instance, however, is provided with a peripheral flange 71 which surrounds a flat face 72 which, in the form illustrated, is 80 rectangular. It is against this face 42 that the different branding elements 73 rest. Each of these elements comprises a flat base 74 and projections 75. The latter constitute the characters or emblems that press 85 upon the body to be branded. The bases 74 of the different branding elements 73 have flat edges so that they will fit together and fit accurately within the confining peripheral wall 71 of the branding iron proper. When the elements 73 are properly assembled they are held in place by a set screw 76 which is threaded through a threaded 90 opening in boss 77 located upon the end of the body 70 of the iron. Where the branding elements sufficiently fill up the space provided upon the iron the screw 76 may abut directly against the edge of the adjacent element 73. Where the elements do not fill up the entire space, as is the case in 95 the particular assemblage illustrated, a filling block 78, upon which no branding face is located, serves to fill up the unoccupied space, and in such case screw 76 bears 100 against the edge of the block 78 while the latter presses against the adjacent element 73. In this way the force applied by the screw 76 is transmitted to the various branding elements and they are all held 105 firmly in place. By reason of the close fitting of the various elements within the flange 71 and upon the base 72, heat from the body 70 of the iron is transmitted with a minimum of loss to the projections 75 which actually engage the body being 110 branded. The close fit of the bases 74 of the branding elements against each other and the pressure exerted by the screw 76 115 also tend to increase the conductivity of the assembled structure.

From the above it will be seen that I have provided a branding iron for use upon torches wherein the heat is well distributed to all parts of the iron which come in contact with the object branded and wherein there is sufficient heat retaining capacity to 120 perform branding operations at a reasonable rate with a high degree of efficiency.

I may state that in carrying out my invention some alterations and modifications 125

may be made in the embodiments illustrated without departing from the spirit and scope of the invention. I, therefore, aim to cover by the terms of the appended claims all such 5 illustrations and modifications as rightly come within the scope of my invention.

What I claim as new and desire to secure by a patent of the United States is:

1. In a device of the class described, a 10 torch having a combustion chamber having an open discharge end, means for supplying fuel under pressure to said chamber, a branding iron having an opposing surface positioned to lie in the path of the flame 15 emitted from the discharge end of said chamber, said surface comprising, first, a flat portion extending substantially at right angles to the axis of the discharge end of said chamber and, second, a plurality of 20 points of substantial length and thickness rising from said flat portion and extending rearwardly therefrom toward said discharge end into position to lie in the midst of the heating flame, a flange projecting rearwardly from the outer edge of said flat portion and serving to revert the flame at said outer edge away from the object being branded, a boss extending rearwardly from the upper portion of said branding iron 25 body and bored out for the reception of the forward end of a retaining rod, said rod, a like bored boss on the upper side of said combustion chamber for the reception of the rear end of said rod, and means for holding the bosses and rod in tight engagement to firmly hold the branding iron on the torch. 30

2. A branding iron comprising a relatively flat body having branding elements on one side and a flame impinging surface 40 on the other, the latter surface comprising, first, a flat portion adapted to lie at right angles to the direction of the applied heating flame, and, second, a plurality of points of substantial length and thickness rising 45 from said flat portion and extending at substantially right angles therefrom into position to be engaged by the applied heating flame, a rearwardly extending flange near the outer edge of said flat portion and surrounding all of said projecting points and serving to revert the heating flame back from the object being branded, a boss recessed for the reception of a holding pin located near the outer edge of the branding iron body between said flange and said projecting points. 50

3. In a device of the class described, a torch having a combustion chamber having an open discharge end, means for supplying fuel under pressure to said chamber, a branding iron having a relatively flat body adapted for holding branding elements and having a flame receiving surface on the other side positioned to lie in the path of the flame 55 emitted from the discharge end of said

chamber, the branding side of said body having a plurality of forwardly extending ribs, a branding element having a suitable branding character on its forward face and a rear portion adapted to abut against the 70 forward face of said body and to lie between said ribs, means for firmly holding said branding element in position against said body and between said ribs, the flame receiving side of said body comprising, first, a flat portion extending substantially at 75 right angles to the axis of the discharge end of said chamber and, second, a plurality of points of substantial length and thickness rising from said flat portion and extending rearwardly therefrom toward the discharge 80 end of said chamber into position to lie in the midst of the heating flame, a flange projecting rearwardly from the outer edge of said flat portion and serving to revert the 85 flame at said edge away from the object being branded, a boss extending rearwardly from the upper portion of said branding iron body at a point between said flange and said points and bored out for the reception 90 of the forward end of a retaining rod, said rod, a like bored boss on the upper side of said combustion chamber for the reception of the rear end of said rod, and means for holding said bosses and rod in tight engagement 95 to firmly hold the branding iron on the torch.

4. A branding iron comprising a relatively flat body adapted for holding branding elements on one side and having a flame impinging surface on the other side, the branding side having a plurality of ribs extending forward from the body, a branding element having a suitable branding character on its forward face and a rear portion adapted to abut against the forward face of said flat body and to lie between said ribs, means for holding said branding element firmly in position against said body between said ribs, the flame impinging surface comprising, first, a flat portion adapted to lie at right angles to the direction of the applied heating flame, and, second, a plurality of points of substantial length and thickness rising from said flat portion and extending at substantially right angles therefrom into position to be engaged by the applied heating flame, a rearwardly extending flange near the outer edge of said flat portion and surrounding all of said projecting points and serving to revert the heating flame back from the object being branded, a boss recessed for the reception of a holding pin located near the outer edge of the branding iron body between said flange and said projecting points. 110

In testimony whereof, I hereunto subscribe my name this 4th day of February, A. D. 1924.

JOHN PETERSON.
